UNITED STATES PATENT OFFICE.

WILLIAM HENRY STONE, OF PORT ANGELES, WASHINGTON.

AIR-COOLER.

1,391,592.

Specification of Letters Patent. Patented Sept. 20, 1921.

Application filed June 8, 1920. Serial No. 387,353.

To all whom it may concern:

Be it known that I, WILLIAM H. STONE, a citizen of the United States, and a resident of Port Angeles, in the county of Clallam and State of Washington, have invented a new and Improved Air-Cooler, of which the following is a full, clear, and exact description.

This invention relates to improvements in air coolers, an object of the invention being to provide an improved apparatus for cooling the air in circulation in a house or room during hot weather.

A further object is to provide an improved apparatus through which the air is compelled to take a circuitous path and pass through screens over which cold water flows, and over saturated cloths or other moisture holding pads to cool the air which finally escapes through an ice chamber and is directed to any point of use.

A further object is to provide an air cooling apparatus which can be manufactured and sold at a reasonably low price, and which can be economically operated to maintain a low temperature.

With these and other objects in view the invention consists in certain novel features of construction, and combinations and arrangements of parts as will be more fully hereinafter described and pointed out in the claim.

In the accompanying drawings—

Figure 1 is a view in longitudinal vertical section illustrating my improved apparatus, the section being taken on the line 1—1 of Fig. 2.

Fig. 2 is a view mainly in vertical section, but partly in front elevation of my improved apparatus.

1 represents a casing which is preferably supported on a suitable base 2. This casing 1 is divided by a vertical series of superimposed partitions or slush boards 3, said partitions extending to one edge of the casing and spaced from the other edge of the casing and having a staggered arrangement so as to compel the air to take a circuitous path upwardly between said partitions as indicated by the arrows in Fig. 1.

Wire mesh or other form of screens 4 are located in the casing and connect the free ends of the partitions with the inner fixed ends of the partitions below so that the air is compelled to pass through said screens. On the uppermost partition 3 an ice pan 5

is located and is provided with perforations 6 at one end through which the water from the melting ice passes over the partition onto the screen 4 below and thence downwardly through the casing. This pan 5 is adapted to contain a block or blocks of ice 7 and the partitions below the ice pan supporting partition are provided with moisture holding pads 8, which may be of cloth or any other suitable material, which becomes saturated with the water, and by evaporation gives off the water to the air as the latter passes over said pads.

A door 10 is provided in the front of the casing giving admission to the upper portion of the casing for the insertion and removal of the ice. 11 represents an air inlet pipe which preferably extends along one wall of the casing 1 and communicates at its lower end with the casing 1 through the medium of a port 12.

13 represents a fan or blower casing which is connected by a pipe 14 with an outlet port 15 in the upper portion of the casing, preferably adjacent the ice pan, as clearly indicated in Fig. 1. In this fan or blower casing 13 a rotary or other form of blower 16 is provided for discharging the air through an outlet 17 to any desired point of use, and I illustrate an electric motor 18 for driving the fan or blower, although, of course, this fan or blower may be operated in any desired way.

In operation, the heated air circulates downwardly through the pipe 11, through port 12, and thence between the series of partitions 3, through the screens 4 and over the pads 8, thus causing a reduction of temperature of the air, and said air as it reaches the upper portion of the casing is cool and finally passes in direct contact with the ice 7 and thence through the outlet pipe 14 and blower casing 13, the circulation being induced by the fan or blower 16 as will be readily understood.

It is obvious that instead of employing a piece of ice 7, a cooling liquid or other agent might be located in the pan 5 to supply the necessary cooling liquid to the screens 4 and pads 8, and a drain cock 18 communicates with the lower portion of the casing to remove any excessive drip therein.

Various slight changes might be made in the general form and arrangement of parts described without departing from the invention, and hence I do not limit myself to

the precise details set forth, but consider myself at liberty to make such changes and alterations as fairly fall within the spirit and scope of the appended claim.

5 I claim:

An air cooler, comprising a casing, a series of superimposed partitions in the casing hav-

ing staggered relation to each other, moisture holding screens connecting the partitions and through which the air is compelled 10 to pass, and moisture holding pads on the partitions.

WILLIAM HENRY STONE.
